UNITED STATES PATENT OFFICE

2,594,968

CHICKEN DRINKING FOUNTAIN

Julian Daniel Miller, Denton, Md., assignor to
himself and Helen Peers Miller, Denton, Md.,
as joint tenants with right of survivorship

Application July 1, 1949, Serial No. 102,481

1 Claim. (Cl. 119—72.5)

1

The invention relates to improvements in chicken drinking fountains in which balanced and weighted water valves are mounted, pointing obliquely downward, on both sides of a water pipe, and inverted V screening is placed over the drain trough beneath the water pipe, and the drain pipe in the trough has a metal cover over the top with small V openings on two sides at the bottom of the trough; and the objects of the improvements are, first, the balanced and weighted water valves permit the mounting of two rows, thereby providing drinking facilities for twice as many chickens on the same length of fountain; second, chickens of all ages can drink from the fountain, since the valves being set on the sides of the pipe, and the height of both the pipe and the drain trough being adjustable, permit sufficient lowering of the fountain, so that one day old chicks can reach the water valves; third, the inverted V screening minimizes the amount of foreign matter entering the drain trough, and the cover over the drain pipe with V openings on the bottom prevents the clogging of the drainage.

The invention is illustrated in the accompanying drawing, in which, Figure 1 is a side view of the complete fountain, parts broken away, since the fountain may be made in various lengths in accordance with the number of chickens to be accommodated; Figure 2, a vertical section on the line 2—2; Figure 3, a section through the balanced water valve on the line 3—3; Figure 4, a detail of the spring hanger for supporting the drain trough and holding the V screening in place; Figure 5, a plan view of the cover over the drain pipe; Figure 6, a section on the line 6—6 of Figure 5, showing the spring that holds the cover in place over the drain pipe; Figure 7, a section on line 7—7 of Figure 5, showing the V openings on the bottom of the cover over the drain pipe.

The fountain is connected to the water supply at 1. A float valve in the tank 2 controls the water level in the tank and supplies water at atmospheric pressure through screened holes 3 in the pipe 4, to the water valves 5, which are mounted to the pipe 4 at spaced intervals on both sides.

The valve 5 consists of a threaded body 5A, a valve stem 6, and a cylindrical weighted portion 6B. The weighted portion 6B has a seat 6C which mates and cooperates with the opening 5B of the body 5A. The lower portion of the valve stem has a neck or reduced section 6D and terminates with a rounded end 6E.

2

When the chickens peck at the water valve stem 6, the stem opens the valve 5, permitting the water to drip. The valve stem 6 is so balanced that it will close the valve as soon as the chicken releases it, and it works perfectly when mounted to the water pipe at obliquely downward angle. As illustrated in Figure 3, the seat of the valve stem 6 is just inside the opening of the valve 5, and is so constructed that there is always water inside of the valve 5, including around 6B portion of the valve stem. The fact that the interior of the valve is always full of water is a great asset in areas where there is mineral or clay deposit in the water supply, since it prevents such substances from drying and caking on the insides of the valve.

The drain trough 7, covered with the inverted V screening 8, is suspended from the water pipe 4 by spring hangers 9 which fit into holes in the 20 sides of the trough and hold the V screening in place. The metal cover 10, over the drain pipe 12, with the V openings at the bottom as illustrated in Figures 5 and 7, prevents the clogging of the drain pipe. The wire loop spring 11, as 25 illustrated in Figure 6, it attached to the inside of the metal cover 10 with the wire loop extending from the bottom of the cover on the outside. The loop part of the wire loop spring is placed in the drain pipe opening in the drain trough 7, 30 and serves to hold the cover 10 tightly in place, since the width of the loop is slightly more than the width of the interior circumference of the drain pipe and its entrance into the drain pipe is effected only by the compression which its 35 spring action permits.

As illustrated in Figures 1 and 2, the water pipe 4 is suspended from between uprights at the apex of the triangular supports 13 and 13A by the hangers 14 and 14A, which are held in place by the cotter pins 15 and 15A through holes in the supports 13 and 13A and the hangers 14 and 14A. Holes at intervals in the hangers 14 and 14A permit the fountain to be raised or lowered in accordance with the size of the chickens to be watered. The wire 16, over the pipe 4 prevents the chickens from roosting on the pipe.

I am aware that prior to my invention, chicken drinking fountains have been made with one row of vertical valves to the fountain, and with 50 horizontal screening over drain trough. I therefore do not claim such a combination.

I claim:

The combination of a chicken drinking fountain including weighted water valves set on opposite sides of a water pipe, said water valves be-

ing mounted in the lower circumference of the pipe and spaced apart by an angle of approximately 70 degrees, said valves consisting of a threaded body enclosing a valve stem with an elongated cylindrical weighted portion having a seat cooperating and mating with a lower restricted opening in the nozzle body, a protruding neck portion of reduced size extending from the seat of the weighted portion and terminating in a rounded end.
